Primary Examiner — David G Muller*Assistant Examiner* — Christina Gabrielle Cosden(74) *Attorney, Agent, or Firm* — Messner Reeves LLP(57) **CLAIM**

The ornamental design for hose securing device, as shown and described.

DESCRIPTION

FIG. 1 is a perspective view of the hose securing device of the present invention.

FIG. 2 is a profile view of the hose securing device of the present invention.

FIG. 3 is a profile view of the hose securing device of the present invention.

FIG. 4 is a bottom up view of the hose securing device of the present invention.

FIG. 5 is a bottom up view of the hose securing device of the present invention; and,

FIG. 6 is profile view of the hose securing device of the present invention.
